CUPEL TOOL

Clement L. Herbert, Berkeley, Calif., assignor to
 American Smelting and Refining Company,
 New York, N. Y., a corporation of New Jersey

Application January 30, 1940, Serial No. 316,304

7 Claims. (Cl. 214—26)

This invention relates to a tool for handling a plurality of articles and is particularly applicable to a tool for charging a bank of cupels into a muffle and subsequently depositing a metallic button charge in each cupel.

In certain assaying operations, such as for gold and silver assaying, it is desirable to deposit a large number of cupels in a muffle at the same time. The muffle may, for example, contain a bank of 100 or more cupels. These cupels must be first inserted in the muffle and brought to temperature, after which it is necessary to deposit in each cupel the sample button to be assayed. The task of dropping such buttons into the cupels manually is disagreeable from the operator's standpoint due to the intense heat of the muffle and it is also a possible cause of inaccuracy in the assaying due to the physical inability of an operator to deposit all of the buttons at the same time. Hence, the buttons are not all subjected to identical operating conditions and there is also a possibility that certain of the buttons may be improperly deposited or may be deposited in the wrong cupels. It is, accordingly, an object of the present invention to provide a tool for depositing the entire bank of cupels in the muffle and then depositing the metallic buttons in the cupels simultaneously so that they are all subjected to the same operating conditions.

Another object is to provide a tool of the above type which is capable of various uses.

Another object is to provide a tool of the type above specified which is so constructed and arranged that the possibility of confusion or of misplacing the metallic buttons in the cupels is eliminated.

Another object is to provide a convenient, dependable and commercially practical tool of the type above specified.

Various other objects and advantages will be apparent as the nature of the invention is more fully disclosed.

Although the novel features which are believed to be characteristic of this invention are pointed out more particularly in the claims appended hereto, the invention itself may be better understood by referring to the following description, taken in connection with the accompanying drawings, in which a specific embodiment thereof has been set forth for purposes of illustration.

In the drawings,

Fig. 1 is a top plan view of the tool in position to receive the cupels;

Fig. 2 is a section taken on the line 2—2 of

Fig. 1 showing the cupels in position with the tray inserted in position to engage and support the cupels when the tool is inverted;

Fig. 2a is a partial section taken on the line 2a—2a of Fig. 2 showing details of construction of the rack;

Fig. 3 is a longitudinal section showing the tool in a muffle in position for depositing the cupels, with the tray partly withdrawn for dropping the cupels onto the muffle hearth.

Fig. 4 is a similar section showing the tool tilted for removal from the muffle after the cupels have been deposited on the hearth;

Fig. 5 is a top plan view of the tool in position to receive the metallic buttons;

Fig. 6 is a longitudinal section showing the tool in the muffle in position to charge the buttons into the cupels, with the tray partly withdrawn for releasing the buttons; and

Fig. 7 is a partial section taken on the line 7—7 of Fig. 6.

Referring to the drawings more in detail, the invention is shown in Figs. 1 and 2 as embodied in a tool comprising a rack 10 having a pair of side runners 11 adapted to position the rack in the muffle for the purpose to be described and having a front wall 12 and a rear wall 13 adapted respectively to engage the sides of the bank of cupels for holding the same in position. A rod 14 is attached by suitable means, such as welding, to the rear wall 13 of the frame 10 and is provided with a handle 15 by which the tool may be manipulated.

A perforated button guide plate 20 is positioned in the frame 10 to support the cupels as in Figs. 1 and 2. The guide plate 20 is provided with a plurality of apertures 21 which are disposed to register with the respective cupels when the latter have been deposited in the muffle. These apertures 21 serve to locate and position the metallic buttons which are to be charged into the various cupels.

A sliding tray 25 is provided, which is mounted on a sleeve 26 having an actuating handle 27. The sleeve 26 is adapted to slide axially of the rod 14 so as to position the tray 25 over the cupels as in Fig. 2 and may be rotated about the rod 14 so as to position the tray 25 beneath the perforated guide plate 20 for forming a support for the buttons as shown in Fig. 6. The frame 10 is formed with side flanges 30 forming, with the plate 20, channels in which the tray 25 is adapted to slide when in the latter position. The tray 25 may have a bevelled front edge 28 to facilitate

the insertion thereof under the cupels as will be described.

The runners 11 are extended rearwardly to form positioning members 31 having shoulders 32 adapted to engage the side walls 33 of a muffle 37 to form a stop for the tool as shown in Fig. 3. Side bosses 34 may be formed on the runners 11 to slide within the side walls 33 and position the tool.

10. In the operation of the above described tool, the tool is first held in the position shown in Figs. 1 and 2 with the tray 25 withdrawn. In this position the cupels 35 are inserted bottom side up on the perforated plate 20. After the cupels have 15 been thus positioned, the tray 25 is advanced axially by means of the handle 27 into position over the up-turned bottoms of the cupels 35, as shown in Fig. 2.

The tool is then inverted into the position shown 20 in Fig. 3 and is inserted on the hearth 36 of a muffle 37 until the shoulders 32 engage the walls 33. The tray 25 is then withdrawn to release the cupels 35 and to permit the same to drop onto the hearth. The rear wall 13 of the frame 10 25 holds the cupels in position during the withdrawal of the tray.

After the cupels have thus been deposited on the hearth, the tool is tipped up as shown in Fig. 4 to disengage the front wall 12 of the frame from 30 the cupels, after which it is readily withdrawn from the muffle.

For charging the samples, the frame 11 is re-inverted to its original position, shown in Figs. 1 and 2 and the sleeve 26 is rotated about the rod 35 14 so as to position the tray 25 beneath the perforated plate 20 as shown in Figs. 5 and 6. The tray is then positioned beneath said perforated plate on the flanges 30 and forms a support for the metallic buttons 40 which are placed in the 40 respective apertures 21 as shown in Fig. 5.

With the buttons in position, the tool is again inserted in the muffle resting upon the runners 11 which are of sufficient width to elevate the frame 10 and tray 25 above the tops of the cupels. 45 After the tool has thus been positioned with the shoulders 32 engaging the walls 33 as before, the tray 25 is withdrawn as indicated in Fig. 6 to release the buttons 40 and to permit the same to fall into the respective cupels. After the buttons 50 have thus been charged, the tool is removed from the furnace and the cupelling operation proceeds.

When the cupels are to be removed from the furnace the frame is again inverted and brought into position over the cupels as indicated in Figs. 55 3 and 4 with the tray 25 retracted. The tray 25 is then advanced beneath the cupels by a suitable actuation of the handle 27, the front wall 12 of the frame serving to hold the cupels in position, while the tray is thus being inserted. After the 60 tray has been properly positioned, the tool is removed from the furnace with the various cupels supported on the tray.

It will be noted that in the above described tool the cupels are all inserted into the furnace 65 or removed therefrom in a single operation and that the metallic buttons are charged simultaneously. Consequently, all of the buttons are subjected to identical cupelling conditions. Furthermore, the time required for charging and removing 70 the cupels and buttons is greatly reduced over that which would be required for charging the separate elements individually.

It is to be understood that the tool is not restricted to the specific purpose above described, 75 but is capable of various other uses where it is

desirable to handle a plurality of elements and to position other elements in registration therewith. Various changes and modifications may be made in the details of construction and mode of operation, as will be readily apparent to a person skilled in the art. The invention is not restricted to the embodiment disclosed herein, but is only to be limited in accordance with the following claims.

What is claimed is:

1. A tool for charging cupels into a muffle comprising a frame, a plate in said frame adapted to support said cupels for charging purposes, said plate having perforations registering with the respective cupels, a tray mounted to slide over said cupels for holding the same in position on said plate and to be withdrawn for releasing said cupels and permitting the same to drop onto a supporting surface when the tool is inserted in the muffle in inverted position, means positioning said tray beneath said perforated plate to 20 form a support for material to be charged into said cupels, said tray being mounted to be slidably withdrawn from said last position for releasing said material and permitting the same to drop into the respective cupels. 25

2. A tool for charging cupels into a muffle comprising a frame, a plate in said frame adapted to support said cupels for charging purposes, said plate having perforations registering with the respective cupels, a tray mounted to slide over said cupels for holding the same in position on said plate and to be withdrawn for releasing said cupels and permitting the same to drop onto a supporting surface when the tool is inserted in the muffle in inverted position, means positioning said tray beneath said perforated plate to 30 form a support for samples to be charged into said cupels, said tray being mounted to be slidably withdrawn from said last position for releasing said material and permitting the same to drop 35 into the respective cupels, said frame having supporting runners adapted to hold the same above the tops of said cupels during said last operation. 40

3. A cupel tool comprising a frame having a perforated supporting plate therein, a rod extending 45 from said frame to provide a handle, a sleeve carried on said rod for axial and rotary movement, and a tray mounted on said sleeve to be positioned above or below said perforated plate by rotation of said sleeve and to be inserted or retracted from 50 registration with said frame by axial movement of said sleeve.

4. A cupel tool comprising a frame having a perforated supporting plate therein, a rod extending 55 from said frame to provide a handle, a sleeve carried on said rod for axial and rotary movement, and a tray mounted on said sleeve to be positioned above or below said perforated plate by rotation of said sleeve and to be inserted or retracted from registration with said frame by axial movement 60 of said sleeve, said sleeve and said rod having handles associated therewith to facilitate the manual manipulation of said tool.

5. A tool for charging cupels into a muffle comprising a frame, a plate in said frame adapted to 65 support said cupels for charging purposes, said plate having perforations registering with the respective cupels, a tray mounted to slide over said cupels for holding the same in position on said plate and to be withdrawn for releasing said cupels 70 and permitting the same to drop onto a supporting surface when the tool is inserted in the muffle in inverted position, means positioning said tray beneath said perforated plate to form a support for samples to be charged into said cupels, said 75

tray being mounted to be slidably withdrawn from said last position for releasing said material and permitting the same to drop into the respective cupels, and means carried by said frame to position the same in said muffle.

5 6. A tool for charging cupels into a muffle comprising a frame, a plate in said frame adapted to support said cupels for charging purposes, said plate having perforations registering with the respective cupels, a tray mounted to slide over said cupels for holding the same in position on said plate and to be withdrawn for releasing said cupels and permitting the same to drop onto a supporting surface when the tool is inserted in the muffle 10 in inverted position, means positioning said tray beneath said perforated plate to form a support for samples to be charged into said cupels, said tray being mounted to be slidably withdrawn from

said last position for releasing said material and permitting the same to drop into the respective cupels, and stop means carried by said frame to position the same in said muffle, whereby the alignment of the samples with the cupels for 5 charging purposes is facilitated.

7. A cupel tool comprising a frame mounting a perforated plate, said frame having side and end walls for confining cupels in a predetermined position with respect to said plate, a tray constituting a support for the cupels when the tool is in inverted position and adapted both to deposit and to pick up the cupels by sliding action of said tray, and means for inserting and retracting the tray in the tool on the opposite side of said perforated plate for charging samples to the cupels. 10 15
